UNITED STATES PATENT OFFICE.

JOHN KNOERL, OF COVINGTON, KENTUCKY, ASSIGNOR OF ONE-HALF TO EDWARD E. WALKER, OF COVINGTON, KENTUCKY.

MEANS FOR SECURING GLASS PANES IN POSITION

974,575.

Specification of Letters Patent.

Patented Nov. 1, 1910.

Application filed November 21, 1908. Serial No. 463,800.

To all whom it may concern:

Be it known that I, JOHN KNOERL, a citizen of the United States, and residing at Covington, Kenton county, State of Kentucky, have invented certain new and useful Means for Securing Glass Panes in Position; and I do declare the following to be a clear, full, and exact description of the invention, attention being called to the accompanying drawing, with the reference characters marked thereon, which forms also a part of this specification.

This invention relates to certain new and useful means for holding a sheet or pane of glass in position within a frame arranged around its edges and adapted to receive it. Practical application of the invention is found by use in connection with sash-frames of windows and similar and related appurtenances used in building-constructions.

In the following specification and particularly pointed out in the claim at the end thereof, will be found a full description of my invention, together with its parts and construction, which latter is also illustrated in the accompanying drawing, in which:

Figure 1, shows in perspective view a window-sash of customary form and construction and provided with my improved means for holding the pane of glass in position which is used to fill it. Fig. 2, in a similar view illustrates manner of inserting the glass. Fig. 3, is a top-view of the sash. Fig. 4, is an enlarged vertical section of it, parts intermediate its height being broken out. Fig. 5, is a part of a horizontal section near one side of the sash. Fig. 6, shows in perspective view and at enlarged scale a part near one of its ends, of a certain member used in my invention.

The drawing shows my invention applied to a sash forming part of, or constituting a window.

A, is the upper sash-rail, B is the lower rail and C—C are the two side-rails.

The rails at their ends where they come together are connected to each other by joints, more or less permanent and made according to customary methods and usages of carpentry. Excepted however is the connection at the ends of one of the rails where it is not permanent, that is to say said rail may be readily detached at any time. When in position however, its connection is such that it firmly occupies its place and forms

with the other rails a rigid sash-frame. The top-rail A is thus connected, a mortise and tenon-joint being used, the joined parts being held together by closely fitting dowel-pins D.

7—7 are the mortises at the upper end of each of the upright rails C, C, and 8 are the tenons, one at each end of the upper rail A and fitted to occupy the mortises.

Perforations d are provided in the engaged, over-lapping parts of the rails, where they come together, to which the dowel-pins D are fitted. In a wooden sash-frame, these dowel-pins are preferably of hard wood, to prevent swelling, and they are closely fitted to retain their position without any other holding means.

The rails on their inner side are all groove for reception of the edges of the glass-panel E, there being a groove a in rail A, a groove b in rail B, and grooves c c in rails C, C. The parallel, opposite sides of the grooves are of even depth and the grooves are so located in the particular side of the rails, that when these latter are connected, they come together at the corners whereby a continuous groove of even depth results which extends all around the four sides of the frame on the inside thereof. A sheet of glass may therefore be inserted as illustrated in Fig 2. The frame as shown there, consists of the rail B and rails C, C permanently connected to it, and is open at one side from which the glass, cut to proper size, is passed in between grooves c c of the opposite, parallel rails C C. After seated in groove b, of rail B the remaining rail A is placed in position and secured by pins D, as shown in Fig. 1. All parts being properly fitted and the glass cut to the right height, its upper edge will be received by groove a of this rail A, as soon as this latter is in position, as shown in Fig. 4.

The grooves in the rails B—C—C exceed in width the thickness of the glass, the excess being occupied by holding strips F, there being one for each of these three grooves and of proper length to entirely fill them between their ends. As to the other dimensions, they are such that they snugly fill the grooves in depth and in width, less the thickness of the glass and without projecting above the grooves so that the intact appearance of the sash-rail is restored without making the presence of these strips no-

2
ticeable. Proper holding fit is obtained by having one of the sides of the strips slightly tapering, as shown at *f*, so that, after pressed into the grooves, they become wedge-seated and frictionally engaged which, considering their position, is sufficient to cause them to remain in place in case shrinkage should reduce their hold. In such case, even if shrunk, the strips would nevertheless remain in position, being sufficiently confined by the sides of the grooves which support them. The connection in this manner of a glass-panel to its frame is clean and quick and of neat appearance after finished, and preferable to 15 a putty-joint.

In case breakage makes replacing of a panel necessary, the detachably connected rail is removed as shown in Fig. 2, strips *F* are pulled out and re-seated after the new 20 panel is in place.

To facilitate quick work, shoulders 9 are formed near the upper ends of rails *C C*, and on their inner sides upon and against which rail *A* comes to a dead stop. Openings *d* which receive the dowel-pins *D* are 25 so bored with reference to these shoulders, that when rail *A* has come to its seat on them, these openings register with each other

so that no difficulty or delay arises when the pins are to be inserted. These shoulders are 30 produced by removing some of the material of each rail on one side of mortise 7.

10 are recesses provided to receive the sash-cords and to permit connection to the sash. 35

Having described my invention, I claim as new:

A window sash comprising a base rail, stiles rigidly connected thereto, said rail and stiles having longitudinal grooves on their 40 inner surfaces, an upper detachable rail having a groove therein, wedge members to clamp a light of glass in said groove, said upper rail having a double tenon at either end and alining holes therethrough, said 45 stiles having a mortise and having a hole therethrough and having a square shoulder to abut said upper rail and thereby aline the holes of the stiles and rails, and a dowel 50 pin adapted to extend into said holes.

In testimony whereof, I hereunto affix my signature in the presence of two witnesses.

JOHN KNOERL.
